DESIGN FOR A CONTAINER FOR NAIL POLISH OR SIMILAR ARTICLE

Carl W. Gardiner, Short Hills, N. J., assignor to
Schnefel Bros. Corporation, Newark, N. J., a
corporation of New Jersey

Application April 3, 1947, Serial No. 138,129

Term of patent 3½ years

(Cl. D58—8)

To all whom it may concern:

Be it known that I, Carl W. Gardiner, a citizen of the United States, residing at Short Hills, in the county of Essex and State of New Jersey, have invented a new, original, and ornamental Design for a Container for Nail Polish or Similar Article, of which the following is a specification, reference being had to the accompanying drawing, forming a part thereof.

Fig. 1 is a top plan view of a container for nail polish or similar article, showing my new design; and

Fig. 2 is a side elevational view thereof.

I claim:

The ornamental design for a container for nail polish or similar article, substantially as shown.

CARL W. GARDINER.
